[57] CLAIM

The ornamental design for magnetic closure clasp, as shown and described.

DESCRIPTION

FIG. 1 is a front elevational view of a magnetic closure clasp showing my new design; the rear being identical in appearance;

FIG. 2 is a left side elevational view thereof;

FIG. 3 is a right side elevational view thereof;

FIG. 4 is a top plan view thereof;

FIG. 5 is a bottom plan view thereof;

FIG. 6 is a top perspective view thereof;

FIG. 7 is an inverted front elevational view of the upper element thereof, the rear being identical in appearance and the lower element being omitted for clarity of illustration;

FIG. 8 is a left side elevational view of FIG. 7;

FIG. 9 is a right side elevational view of FIG. 7;

FIG. 10 is a bottom plan view of FIG. 7;

FIG. 11 is a top plan view of FIG. 7;

FIG. 12 is a bottom perspective view of FIG. 7;
FIG. 13 is a front elevational view of the lower portion thereof, the rear being identical in appearance, and the upper portion being omitted for clarity of illustration;

FIG. 14 is a left side elevational view of FIG. 13, the right side being identical in appearance;

FIG. 15 is a top plan view of FIG. 13;

FIG. 16 is a bottom plan view of FIG. 13; and

FIG. 17 is a top perspective view of FIG. 13.
